Primary Examiner — Terry Wallace(74) *Attorney, Agent, or Firm* — Ryan Kromholz & Manion, S.C.**CLAIM**

(57) The ornamental design for a beverage container dispensing cooler, as shown and described.

DESCRIPTION

FIG. 1 is a front perspective view of a beverage container dispensing cooler showing our new design.

FIG. 2 is a front view thereof.

FIG. 3 is a rear view thereof.

FIG. 4 is a left side view thereof.

FIG. 5 is a right side view thereof; and,

FIG. 6 is a top plan view thereof.

The broken lines shown in the FIGURES are for illustration purposes only and do not form part of the claimed invention.
